SWITCHING OF METAL STOCK AND THE
LIKE

Charles W. Hawthorne, Worcester, Mass., assignor to Morgan Construction Company, Worcester, Mass., a corporation of Massachusetts

Application July 27, 1936, Serial No. 92,836

20 Claims. (Cl. 193—39)

The present invention relates to a switching means and method by which pieces of stock, arriving in overlapped relation at a switching point, can be directed selectively into any one of a plurality of paths or channels arranged to receive such stock.

The invention is applicable to a wide variety of uses; for illustrative purposes, I have shown it applied to the handling of hot bars or billets delivered endwise successively from a heating furnace and destined for further reduction, in a plurality of parallel paths, as by rolling in a multi-strand rod mill, i. e., a mill which delivers its product in a plurality of lines or strands.

The invention enables an operator, by suitable manipulation of a single control device, to obtain very readily the proper distribution of the arriving pieces to the several paths or channels that lead from the switching point,—the switching apparatus being so arranged and operated that no hindrance to the delivery of a newly-arriving piece into any selected path or channel is imposed by the concurrent movement through or across the apparatus of other pieces which have been previously directed into adjacent channels or paths; other and further objects and advantages of the invention will appear from the following detailed description thereof, taken in connection with the accompanying drawings, in which—

Fig. 1 is a view in side elevation, partly in section, of apparatus involving the invention.

Fig. 2 is a front elevational view of such apparatus.

Fig. 3 is a plan view of the apparatus shown in Figs. 1 and 2.

Figs. 4, 5, 6 and 7 are fragmentary partly diagrammatic views illustrating different positions of the operating devices for the switching member.

Fig. 8 is a sectional view of a valve mechanism which is movable to produce the several positions of the operating mechanism shown by Figs. 4, 5, 6 and 7.

Fig. 9 is a cross-sectional view on the line 9—9 of Fig. 8.

Fig. 10 is a view similar to Fig. 9, but showing the valve member in a different position.

Fig. 11 is a detached view, partly in section, of the valve member.

Fig. 12 is a perspective view of said valve member.

Fig. 13 is a diagrammatic plan view, illustrating the operation of the apparatus.

Like reference characters refer to like parts in the several figures.

In Fig. 13 is shown diagrammatically, by way of example, a conventional billet-heating furnace 1, of the type through which the billets move 5 broadside in a row; each billet, as it arrives at the discharge end of said furnace, is pushed out endwise through a suitable opening 2, by a movement which carries the billet's front end clear across my improved switching apparatus, designated as a whole by the numeral 3. Such switching apparatus, as hereinafter described, is so operated as to direct such advancing end of each billet into one or the other of four separate paths or channels 4, 5, 6 and 7, arranged in a row 15 alongside the switching apparatus and constituting, in the apparatus shown by Fig. 13, the receiving guides for the initial stand of rolls 8 of a multi-strand rod mill, the latter being arranged in the well-known manner to reduce and deliver 20 its product in four parallel lines or strands 9, 9, 9, 9, as indicated by the broken lines in Fig. 13. The switching apparatus of my invention is preferably interposed between the row of guide entrances 4, 5, 6 and 7 and a suitable support or platform 10 adjacent the delivery opening 2 of furnace 1; said platform 10 is substantially at the same level as the bottom or supporting surfaces of the guide openings 4, 5, 6 and 7. The switching apparatus proper consists principally of two elements, viz., a supporting structure 11 adapted to be raised and lowered, and a switching member 12 adapted to move back and forth on said supporting structure.

The supporting structure is shown in Figs. 1, 35 2 and 3 as provided by a pair of parallel rails 13, 13 connected at opposite ends by cross-members 14, 14; each cross-member 14 is supported by a pair of rocker arms 15, 15, the latter extending upwardly in parallel relation from two cross-shafts 16, 16 which are journalled in suitable stationary supports 17, 17 at opposite ends of the structure. To one of said shafts 16 is keyed or otherwise secured an operating arm 18, whose free end, by mechanism to be hereinafter described, is adapted to be raised and lowered to procure raising and lowering of the supporting structure 11 in a parallel motion about the centers or axes of cross-shafts 16, 16.

The rails 13, 13 support the wheels or rollers 50 18, 19 of the switching member 12 which, as shown in Fig. 3, substantially bridges the space between the platform 10 and the channels 4, 5, 6 and 7. On the upper surface of member 12 are provided upstanding guide flanges 20 and 21 55

which are widely spaced apart on the side receiving the stock from platform 10, but which converge to form a relatively narrow mouth 22 on the side adjacent the guides or channels 4, 5, 6 and 7,—the mouth 22 being of a width to register with only one of such guides or channels. Pivotally connected at 23 to the member 12 is a draw bar 24 which, at its other end, provides one or more notches 25 to engage over a pin 26 provided by a rocker arm 27 which extends upwardly from a shaft 28. Said shaft 28, journalled in suitable supports 29, provides another arm 30, to the end of which is hung a suitable weight 31, the latter tending to rock the shaft 28 counterclockwise, thereby to force the member 12 to its extreme left hand position, Fig. 3, with the mouth 22 alined with the left hand guide entrance or channel 4, as shown.

Operating oppositely on arm 30 from weight 31 is a lifting cable or connection 32 which, by mechanism to be hereinafter described, is subjected to upward movements of varying lengths, thereby to draw the switching member 12 to the right, Fig. 3, for alining the mouth 22 selectively with one or the other of the remaining channels or guide entrances 5, 6 or 7. It will be understood that no actual registration of mouth 22 with any of the guide entrances 4, 5, 6 or 7 occurs when the supporting structure 11 is in the lowered position indicated by Fig. 1, since in that position, the mouth 22 is below the level of said guide entrances; not until said supporting structure 11 is shifted into its upper position, by upward pull on arm 18, does such registration occur, and in order to maintain such registration with whichever guide entrance has been selected to receive the bar or billet, the member 12 is preferably provided with a projecting lug 33 which enters, upon the elevation of the supporting structure, in one of a series of recesses 34, 34 underlying and corresponding in number and arrangement to the entrances 4, 5, 6 and 7,—thus to hold the member 12 while so elevated against any displacement from the selected position. It follows, therefore, that the back and forth positioning movement of switch member 12 on the supporting structure must occur when the latter is in its lowered position; the elevation of said supporting structure to register mouth 22 with the selected opening or entrance is made to take place after the switching member 12 has been shifted to the desired position by appropriate upward movement of the cable or connection 32.

Said cable 32, as shown in Fig. 1, has its upper end pivotally secured to the fulcrum 35 of a lever 36, to the ends of which are pivotally secured the upwardly extending links 37 and 38. One of said links, 38, is pivotally connected to the fulcrum 39 of a second lever 40, and to the end of lever 40 are pivotally secured the upwardly extending links 41 and 42. The three links or members 37, 41 and 42 are preferably made adjustable in length by means of turnbuckles 43, 43, 43, and each said link or member at its upper end is operatively connected at 44, 44, 44 to its own individual fluid pressure control device,—such devices, three in number and marked a, b and c, being piston and cylinder units of conventional construction, each with its piston rod connected at 44 with the associated link or member 37, 41 or 42, respectively.

Fluid under pressure is supplied to and exhausted from the devices a, b and c for the raising and lowering of their respective pistons by way of the separate pipes or conduits 45, 46 and

47, respectively, the latter communicating, as shown in Fig. 8, with three spaced ports 45', 46' and 47', respectively, of an interior chamber 48 formed by the bore of a valve casing 49. This valve casing forms part of a control valve mechanism which is suitably located in relation to the switching point so that the operator by manipulation thereof, as hereinafter described, may set the switching member 12 in any desired position for directing the next-arriving piece of stock into any one of the guide entrances 4, 5, 6 or 7.

Referring to Figs. 8 to 12 inclusive, the inlet of pressure fluid to bore 48 is by way of a port 50, which is connected by pipe 51 to any suitable source of pressure fluid supply. The outlet or exhaust of pressure fluid from the valve casing is by way of a port 52, to which may be connected a suitable return or exhaust pipe 53. Fitted for sliding movement and also for turning movement in the bore 48 is a valve member of the construction shown by Figs. 11 and 12, said member beyond its cylindrical barrel or bearing portion 54 being recessed on opposite sides, as shown at 55, 55, and beyond said recesses having a short cylindrical end portion 56 that fits said bore. In the extreme right hand position of said valve member shown by Fig. 8, the pressure fluid supply port 50 is barely overlapped by the recessed portions 55, 55, there being a transverse passage 57 across the narrow end portion of the valve member which maintains constant communication between said two recessed portions 55, 55. Also, in this narrow working portion of the valve member, is formed an elongated slot 58 from which opens a passage or port 59 through portion 56 into the chamber 48.

The valve member is operated by a lever or handle member 60, the latter being pivoted at 61 to a bracket 62 which projects from a ring 63 that encircles a cylindrical portion 64 of the valve casing 49 and is free to turn thereon, i. e., on an axis substantially corresponding to the longitudinal axis of the valve member. However, said ring is restrained from any endwise movement, being engaged on one side by a shoulder or collar 65 of the valve casing, and on the other side by a threaded ring 66 which is screwed on to the end of the valve casing. The handle or operating lever 60 passes through a diametrical slot 67 in the barrel portion 54 of the valve member, the portion received in said slot preferably having rounded edges 68 to avoid lost motion or any tendency to bind on the adjacent surfaces of the slot, as the valve is moved back and forth by rocking of the lever on its pivotal axis 61.

A stationary bracket 69, preferably secured to the valve casing, has a transverse portion 70 which provides a suitable bearing support or guide for the reduced portion or stem 71 of the valve member. The longitudinal portion of said bracket 69 provides a series or row of suitably spaced recesses or notches w, x, y and z, adapted to receive the valve operating lever 60 in each of the four (or more) longitudinal positions into which the valve member is movable, for controlling, as hereinafter described, the admission and discharge of pressure fluid to and from the devices a, b and c. The freedom of ring 63 to turn on the longitudinal axis of the valve member allows operating lever 60 to have rocking motions about said axis, for movement into and out of the aforesaid notches w, x, y, z,—and the valve member itself partakes of such rocking motions, due to the passage of lever 60 through the slot 67. That is to say, with the lever 60 received in

any one of the notches *w*, *x*, *y*, *z*, the angular position of the valve member is that illustrated in Fig. 9, whereas with the lever 60 rocked outwardly to clear such notches or recesses *w*, *x*, *y*, *z*, the angular position of the valve member is that illustrated in Fig. 10,—there being a suitable stop, not shown, which limits the turning movement of ring 63 on the withdrawal motion of lever 60 from any of the four positions *w*, *x*, *y*, *z*, and thus 10 keeps the valve member from moving beyond the angular position shown in Fig. 10.

As shown in Figs. 9 and 10, the valve casing 49, in substantially the same transverse zone as the port 50, provides a port 72 approximately 90° removed from the port 50, the port 72 being connected by a pipe 73 to a fourth fluid pressure control device *d* (Fig. 1), of substantially the same construction as the devices *a*, *b* and *c*. The piston rod of device *d* is connected, preferably 20 through an adjustable turnbuckle link 74, to a cable 75, the latter, as shown in Fig. 2, having depending therefrom a rod 76 which is pivotally attached at 77 to the operating arm 18 for raising and lowering the supporting structure 11 on 25 which rides the switching member 12. Preferably, rod 76 is surrounded by a coiled spring 78, confined between a collar 79 on said rod and a stationary standard 80,—the function of said spring being to cushion the up and down motions 30 of the supporting structure 11, as obtained by the admission of pressure fluid to and the discharge of pressure fluid from the device *d*. The operation of the apparatus is as follows:

With the valve operating lever 60 in the position shown by Fig. 8 and rocked over into the notch *w*, the valve member occupies the angular position shown in Fig. 9,—a recess 55 thereof establishing communication between ports 50 and 72, so that the pressure fluid has access by pipe 73 to the device *d*; this drives the piston of said device *d* upwardly, and thereby elevates the supporting structure 11 and with it the switching device 12, the latter's mouth 22 being thereby registered with the particular guide entrance (in this instance the entrance 4) with which the mouth 22 is aligned when the valve is in its extreme right hand position shown by Fig. 8. That is to say, this extreme right hand position of the valve leaves open to exhaust all three of the ports 45', 46' and 47' that are associated with the fluid pressure devices *a*, *b* and *c* respectively, in consequence of which all three of the pistons of said devices remain at their lowest points in the respective cylinders; thus the point or connection 35 is held down by weight 31 at the lowest level (Fig. 4) which said point or connection 35 can descend to; with the connection 35 at this level, the switching member 12 occupies the extreme left hand position shown by Fig. 3.

With the mouth 22 thus registered with guide entrance 4, as shown in Fig. 3, it will be clear that the advancing front end of a bar or billet which is pushed across platform 10 and onto switching member 12 in the general direction of the guide entrances 4, 5, 6 and 7, will invariably be directed into the entrance 4 by its engagement with one or the other of the converging guide flanges 20 and 21. Assume now that such bar or billet so directed into entrance 4 has been seized in the reducing roll pass to which said entrance 4 delivers, and is being drawn or pulled by the action of said reducing rolls across the platform 10 and the switching member 12; assume also that the operator elects

to have the next bar or billet which is pushed outwardly onto platform 10 and switching member 12 delivered to the guide entrance 5. The operator proceeds at once to arrange the apparatus for such delivery, notwithstanding the fact that the bar or billet first referred to may be still in the process of being drawn across the switching apparatus into guide entrance 4; to arrange the apparatus for such delivery of the next bar or billet into guide entrance 5, he shifts the operating lever 60 out of the notch *w* and into the notch *x*. The rocking movement of the valve incident to pulling the lever 60 out of notch *w*, throws said valve into the position shown in Fig. 10, where the valve slot 58 comes into registry with port 72 and thereby immediately exhausts the pressure fluid from device *d*, causing the supporting structure 11 and switching member 12 to descend to the depressed position shown by Fig. 1. This carries the lug 33 clear of the recesses 34, 34 so that the switching member 12 is freed for movement on the rails 13, 13.

This lowering of the switching member 12 does not disturb in any way the continued passage of the bar or billet first referred to into the guide entrance 4, nor does any disturbance to such stock passage arise from the ensuing longitudinal movement of the lowered switch member 12, when the lever 60, freed from notch *w*, is shifted to a position opposite the next notch *x*. That is to say, such first piece of stock continues to be drawn by rolls 8 across the space immediately above the lowered switching member 12, and the passage of said stock across said space is at a level high enough to clear the left hand guide flange 20 which, by any right hand movement of switching member 12 from the position shown in Fig. 3, will be moved into a position underlying a bar or billet which is being drawn into guide entrance 4.

The above described movement of valve lever 60 to a position opposite the notch *x* shifts the valve member 54 far enough to carry its cylindrical portion 56 beyond the port 47', thus causing the valve recess 55 to connect the port 47' with fluid supply port 50. This admits pressure fluid to the device *c* for the elevation of the latter's piston, as shown in Fig. 5, causing the right hand end of lever 40 to move upwardly; this raises to a limited extent the point 39, which in turn causes the point 35 to move upwardly a short distance, i. e., enough to draw the switching member 12, through cable 32, to the right, so that the mouth 22 will be positioned just below the guide entrance 5. During this left hand movement of valve 54, the registration of slot 58 with port 72 (Fig. 10) is maintained, so that the piston of device *d* remains at the bottom of its cylinder, this preventing any elevation of switching member 12 during its above-described right hand movement. But when the operator completes the valve movement by throwing the lever 60 into the selected notch *x*, the angular movement thus imparted to said valve (see Fig. 9) restores the flow of pressure fluid into port 72 for the immediate lifting of the piston of device *d*,—thus returning the supporting structure to its elevated position which disposes the mouth 22 in registry with the guide entrance 5.

In consequence, the advancing front end of the next bar or billet pushed out from furnace 1 will be directed by the converging guide flanges into said entrance 5,—this taking place without interference in any way with the continued passage into entrance 4 of the first-referred to bar 75

or billet, the latter simply riding over the guide flange 20 when the switch member 12 is in its elevated position. Assume now that with two different bars or billets being drawn by rolls 8 across the switching member, one piece into the entrance 4 and the other into the entrance 5, the operator elects to have the next-arriving piece enter the guide entrance 6; to set the switching member for this purpose, the operator withdraws the valve lever from notch *x* and moves it into notch *y*. As before, the rocking of the valve 54, incident to withdrawal of valve lever 60 from the notch which it occupies, causes the switching member to be lowered,—a prerequisite to its endwise movement. The valve's endwise movement, produced by shifting of lever 60 to a point opposite the notch *y*, carries the valve portion 60 just beyond the port 46' so as to admit pressure fluid not only to the device *c* as above described, but also to the device *b*. The resulting elevation of the piston of device *b* raises the left hand end of lever 60 as shown in Fig. 6, and thereby produces, through further raising of point 39, an additional upward movement of point 35 to shift switching member 12 on rails 13 a sufficient distance to dispose the mouth 22 of said member just below the guide entrance 6. Thereupon, when the operator completes the valve movement by throwing the lever 60 into the selected notch *y*, the angular movement thus imparted to said valve (see Fig. 9) restores the flow of pressure fluid into port 72 for the immediate lifting of the piston of device *a*,—thus elevating the supporting structure to dispose the mouth 22 in registry with the guide entrance 6.

In this position of the switching member, both of the previously directed pieces being drawn into the entrances 4 and 5 will ride over the flange 20, and the next-arriving piece will be directed by flanges 20 and 21 into guide entrance 6. The same procedure as above described can be employed to set the switching member in position to direct the next piece pushed out from the furnace into the guide entrance 7,—the valve lever 60 in this instance being shifted into the notch *z* by a left hand movement which carries the valve portion 56 past the port 45',—thus admitting pressure fluid to the device *a* as well as to the devices *b* and *c*. In this situation, with the elevation of all three pistons of devices *a*, *b* and *c*, the point 35, as shown in Fig. 7, is raised to its highest position, carrying the switching member 12 to its extreme right hand position, so that when the valve lever 60 is rocked over into notch *z*, the mouth 22 will register with the guide entrance 7. Fig. 13 illustrates graphically a situation in which successively pushed-out pieces of stock 5', 6' and 7' have been directed, respectively, into guide entrances 5, 6 and 7 and are being drawn by rolls 8 across the space occupied by the switching member 12. The latter, having directed the last-arriving piece 7' into guide entrance 7, must now be shifted so as to direct the next-arriving piece into the only empty guide entrance, namely, the guide entrance 4. For this purpose, the operator withdraws the valve lever 60 from notch *z* (with consequent lowering of the switching member) and repositions said valve lever in notch *w*, the notch corresponding to guide entrance 4. In this manipulation, the valve's endwise movement exhausts the pressure fluid from all three devices *a*, *b* and *c*, allowing the weight 31 to move the switching member 12 to its extreme left

hand position, (Figs. 3 and 13), thus disposing the guide flange 21 beneath all three of the pieces of stock 5, 6' and 7' that, as assumed above, are being drawn along by the rolls 8. With the elevation of the switching member 12 at the completion of the valve movement, (the rocking of valve lever 60 into notch *w*), the guide flange 21, which is purposely made somewhat higher than the guide flange 20, will lift the three passing pieces high enough to allow the next-pushed-out piece 4' (Fig. 13) on the furnace floor to pass under said three pieces and be directed without interference into the guide entrance 4.

I claim,

1. The combination with a plurality of stock-conveying paths having their entrances substantially in a row, of a movable guide device common to all the entrances of said row and adapted by lateral engagement with successive pieces of stock moving toward said entrances to direct each piece into a selected path, and operating means for said guide device to initially free it from lateral engagement with a so-directed piece of stock passing across same into one of said paths and then to dispose said guide device, still free from lateral engagement with said passing piece, in operative relation with the entrance of another of said paths.

2. The combination with a plurality of stock-conveying paths having their entrances substantially in a row, of a movable guide device common to all the entrances of said row and adapted by lateral engagement with successive pieces of stock moving toward said entrances to direct each piece into a selected path, and operating means for said guide device to initially free it from lateral engagement with a piece of stock passing across same into one of said paths and then to dispose said guide device in operative relation with the entrance of another of said paths, said operating means comprising fluid pressure means for shifting said guide device at right angles to said row of entrances and other fluid pressure means for shifting said guide device substantially parallel to said row of entrances.

3. The combination with a plurality of stock-conveying paths having their entrances substantially in a row, of a movable guide device common to all the entrances of said row and adapted by lateral engagement with successive pieces of stock moving toward said entrances to direct each piece into a selected path, and operating means for said guide device to initially free it from lateral engagement with a piece of stock passing across same into one of said paths and then to dispose said guide device in operative relation with the entrance of another of said paths, said operating means comprising fluid pressure means for shifting said guide device at right angles to said row of entrances and other fluid pressure means for shifting said guide device substantially parallel to said row of entrances, and a single valve for controlling both of said fluid pressure shifting means.

4. Apparatus for directing successive pieces of moving stock into any one of a plurality of stock-conveying channels arranged substantially in a row, comprising a table having guide means thereon, fluid pressure means for shifting the table in a direction substantially at right angles to the row of channels to move the guide means into and out of operative relation to the channels, fluid pressure means for shifting said table in a direction substantially parallel to the row

of channels, and a single valve for controlling both shifting means to cause the first shifting means and the second shifting means to operate in predetermined sequence.

5. The combination with means for the endwise delivery of a succession of stock pieces, of more than two stock-receiving and conveying media having their entrances arranged in a row across the line of stock delivery, stock-forwarding means associated with each of said entrances for advancing any piece delivered thereto at a speed so related to the recurring operations of said delivery means that said piece's tail end is overlapped by the first end of the next-delivered piece, a stock-switching device adapted to be moved into registration selectively with each of said entrances, and means for procuring the travel of said device, when moving from its registration with one entrance to registration with any other selected entrance along a path offset from said row, whereby to avoid registration of said device with an unselected intervening entrance.

6. The combination with endwise delivery means for a succession of stock pieces, of more than two stock-receiving media, each arranged to continue the endwise movement of pieces so delivered, a switching device interposed between said delivery means and the entrances to said stock-receiving media, said switching device being movable selectively into registration with each of said entrances, and means for preventing the movement of said switching device from its registration with one entrance into registration with another entrance except in a plane offset from and substantially parallel to the plane of said entrance.

7. The combination with endwise delivery means for a succession of stock pieces, of more than two stock-receiving media, each arranged to continue the endwise movement of pieces so delivered, a switching device interposed between said delivery means and the entrances to said stock-receiving media, said switching device being movable selectively into registration with each of said entrances, means for preventing the movement of said switching device from its registration with one entrance into registration with another entrance except in a plane offset from and substantially parallel to the plane of said entrances, and means for shifting said switching device between said entrance plane and said offset plane.

8. In apparatus of the class described, a group of more than two stock-conveying channels served by a common endwise delivery means for a succession of stock pieces, in combination with an interposed switching device adapted to be registered selectively with any of said channels, and operating means for shifting said switching device from one channel to any other by an initial movement into a plane offset from and substantially parallel to the plane of said channels, an intermediate movement in said offset plane to a position substantially alining but out of registry with the selected channel, and a final registry movement.

9. The combination with means for the endwise delivery of a succession of elongated pieces of stock, of stock-forwarding means having a group of more than two entrances all served by said delivery means and arranged in a row across the line of stock delivery, said stock-forwarding means operating at a speed so related to said delivery means' recurring operations that the tail

end of a piece being forwarded by said forwarding means is overlapped by one or more of the next-delivered pieces, a switching member in the path of stock delivery, and selectively registrable with any of said entrances, to direct an approaching piece thereto, and operating means for said switching member to initially free it from lateral engagement with a so-directed piece of stock passing into one of said entrances, and then to move said member along a path offset from said row and into registration with any other selected entrance, whereby to avoid registration of said member with an unselected intervening entrance.

10. The combination with means for the endwise delivery of a succession of elongated pieces of stock, of stock-forwarding means having a group of more than two entrances all served by said delivery means and arranged in a row across the line of stock delivery, said stock-forwarding means operating at a speed so related to said delivery means' recurring operations that the tail end of a piece being forwarded by said forwarding means is overlapped by one or more of the next-delivered pieces, a stock guiding member in the path of stock delivery and movable into different operative positions corresponding in number and arrangement to said row of entrances, whereby to direct an approaching piece to any selected one of said entrances, and operating means for said guiding member to initially free it from lateral engagement with a so-directed piece passing into one of said entrances, and then to move said guiding member along a path offset from said row and into registration with any other selected entrance, whereby to avoid registration of said guiding member with an unselected intervening entrance.

11. The combination with means for the endwise delivery of a succession of elongated pieces of stock, of stock-forwarding means having a group of more than two entrances all served by said delivery means and arranged in a row across the line of stock delivery, said stock-forwarding means operating at a speed so related to said delivery means' recurring operations that the tail end of a piece being forwarded by said forwarding means is overlapped by one or more of the next-delivered pieces, a stock guiding member in the path of stock delivery and movable into different operative positions corresponding in number and arrangement to said row of entrances, whereby to direct an approaching piece to any selected one of said entrances, and operating means for said guiding member to initially free it from engagement with a so-directed piece passing into one of said entrances, and then to move said guiding member along a path offset from said row and into operative relation to any other selected entrance, whereby to avoid operative association of said guiding member with an unselected intervening entrance.

12. The combination with means for the endwise delivery of a succession of elongated pieces of stock, of stock-forwarding means having a group of more than two entrances all served by said delivery means and arranged in a row across the line of stock delivery, said stock-forwarding means being operated at a speed so related to the recurring operations of said delivery means that the tail end of a piece being forwarded by said forwarding means is overlapped by one or more of the next-delivered pieces, a switching member adapted to be registered in turn with all of said entrances, to distribute successive approaching

pieces of stock between them, and means for withdrawing said member from registration with one entrance, and for thereafter shifting it selectively along a path offset from said row into registration either with an adjacent entrance or with another of said entrances beyond said adjacent entrance.

13. The combination with means for the endwise delivery of a succession of elongated pieces of stock, of stock-forwarding means having a group of more than two entrances all served by said delivery means and arranged in a row across the line of stock delivery, said stock forwarding means being operated at a speed so related to the recurring operations of said delivery means that the tail end of a piece being forwarded by said forwarding means is overlapped by one or more of the next-delivered pieces, a switching member adapted to be registered in turn with all of said entrances, to distribute successive approaching pieces of stock between them, means for withdrawing said member from registration with one entrance, and for thereafter shifting it selectively along a path offset from said row into registration either with an adjacent entrance or with another of said entrances beyond said adjacent entrance, and means on said member brought into action by either of said shifting movements aforesaid for elevating any pieces then in passage to said entrances above the delivery level of the next-delivered piece, whereby the latter is directed to its selected entrance without obstruction from said pieces then in passage.

14. In apparatus of the class described, an endwise delivery means operating successively on single elongated pieces of stock, more than two receiving channels for the delivered pieces, with their entrances arranged in a row transverse to the line of stock delivery, stock-advancing means associated with each channel for continuing the endwise movement of each piece at a speed so related to the recurring operations of said delivery means that said piece's tail end is overlapped by the advancing first end of the next-delivered piece, a guide device for the stock adapted to be registered, selectively, with any one of said entrances to direct the next-delivered piece into a selected channel, means for moving said device from its registry with one entrance into registry with any other of the remaining entrances of said row of three or more entrances, and means for constraining such movement to a path offset from said row, whereby to avoid registration of said device with an unselected intervening entrance.

15. The combination with stock-forwarding means having more than two entrances arranged substantially in a row, of a movable guide device common to all said entrances and adapted by lateral engagement with successive pieces of stock moving toward said entrances to direct each piece into a selected entrance, and operating means for said guide device to initially free it from lateral engagement with a so-directed piece of stock passing across same into one of said entrances and then to move said device along a path offset from said row and into registration with another selected entrance, whereby to avoid registration

of said device with an unselected intervening entrance.

16. The combination with stock-forwarding means having more than two entrances arranged substantially in a row, of a movable guide device common to all said entrances and adapted by lateral engagement with successive pieces of stock moving toward said entrances to direct each piece into a selected entrance, means to move said device back and forth as desired along a path offset from said row, and means to move said device between said path and said row and vice versa, whereby the device can be moved from registration with one entrance into registration with a selected non-adjacent entrance without registration with an unselected intervening entrance.

17. The combination with stock-forwarding means having more than two entrances arranged in a substantially horizontal row, of a movable guide device common to all said entrances and adapted by lateral engagement with successive pieces of stock moving toward said entrances to direct each piece into a selected entrance, means to move said device back and forth as desired along a substantially horizontal path offset downwardly from said row, and means to raise and lower the device between said path and said row, whereby the device can be moved from registration with one entrance into registration with a selected non-adjacent entrance without registration with an unselected intervening entrance.

18. The combination with stock-forwarding means having more than two entrances arranged in a substantially horizontal row, of a movable guide device common to all said entrances and adapted by lateral engagement with successive pieces of stock moving toward said entrances to direct each piece into a selected entrance, means to move said device back and forth as desired along a substantially horizontal path offset downwardly from said row, and means to raise and lower the device between said path and said row, the guide device being shaped as a channel which opens upwardly, whereby the device can be moved from registration with one entrance while a piece of stock is passing therethrough and then into registration with a selected non-adjacent entrance without registration with an unselected intervening entrance.

19. In apparatus of the class described, a switching member adapted to be disposed, selectively, in any one of a plurality of operating positions, operating means therefor, comprising a plurality of actuators, and connecting devices between said member and said actuators arranged to produce varying amounts of motion to said member in direct proportion to the number of actuators rendered active.

20. In apparatus of the class described, a switching member adapted to be disposed, selectively, in any one of a plurality of operating positions, actuating means therefor comprising a plurality of hydraulic pistons, and connecting devices between said pistons and said member arranged to transmit to said member different movements of varying extent, depending upon the number of said pistons rendered active for the movement of said member.

CHARLES W. HAWTHORNE.
